INVENTOR

UNITED STATES PATENT OFFICE.

THEODORE F. TAYLOR, OF BROOKLYN, NEW YORK.

AUTOMATIC-TELEGRAPH SYSTEM.

SPECIFICATION forming part of Letters Patent No. 293,111, dated February 5, 1884.

Application filed September 18, 1883. (No model.)

To all whom it may concern:

Be it known that I, THEODORE F. TAYLOR, a citizen of the United States, residing in Brooklyn, in the county of Kings and State of New York, have invented certain new and useful Improvements in Automatic Telegraphy, of which the following is a specification.

This invention relates to that class of telegraphs in which the electric signals or impulses which represent the letters or other characters of a communication are transmitted over the main line with great rapidity by means of automatic mechanism.

The object of my invention is to provide a system of electric circuits and apparatus at the terminal station of such a line, so that any desired number of different operators may be simultaneously engaged in preparing matter for transmission, the copy being divided into any required number of sections or "takes," each of which may consist either of one or more distinct messages or of one or more parts of a single communication. The matter which has thus been prepared by the different operators is transmitted in proper order of succession and with great rapidity over a single conductor without entailing any material loss of time between the transmission of the different messages or portions of messages thus prepared.

The invention also comprises means whereby one or more receiving-instruments may be placed in connection with the main line, in lieu of one of the transmitting-instruments.

The result obtained by the use of my invention is the more rapid and uninterrupted consecutive transmission of separately-prepared messages or parts of messages over the single line than has heretofore been possible.

The particular organization of the invention hereinafter set forth has been developed with special reference to the use and adaptation in connection with a method or system of automatic transmission for which United States Letters Patent were issued to W. A. Leggo, March 15, 1881.

In practically operating an automatic system of this particular kind it has heretofore been usual for the different operators at the sending-station to simultaneously prepare separate portions of the matter for transmission by inscribing them in conventional sym-

bols, composed of insulating-ink, upon metallic cylinders, the line of characters passing helically around the cylinder from one of its ends to the other. The cylinders which have thus been charged with the prepared matter are then successively placed in the circuit of the main line, and their contents automatically transmitted one after another therethrough by causing them to revolve beneath a circuit-closer or stylus in a manner fully set forth in the above-mentioned Letters Patent of Leggo, to which reference may be had for a more particular description. When the matter contained upon the surface of any one cylinder has thus been transmitted, it has been necessary to replace that cylinder by another, and the automatic transmission has necessarily been interrupted or superseded during the time required to substitute one cylinder for the other, and to effect the adjustment of parts required to accommodate the new cylinder. The loss of time thus entailed seriously diminishes the actual working capacity of the line. In the organization hereinafter to be described this loss of time in transmission is entirely avoided. Each cylinder is placed in an independent local circuit, together with the apparatus which is necessary to prepare the matter which may be assigned to it. I also provide an independent branch of the main line for each transmitting-cylinder, which is so arranged as to be capable of being placed in connection with the main-line conductor itself at the proper moment by the managing operator of the station. When any one of the branch conductors is thus connected, it forms the terminal portion of the main conductor. The instant that such connection has been established the operator in charge of the particular cylinder is notified by an electric signaling apparatus to commence the transmission of the matter with which it is charged, and so soon as the matter has been transmitted the managing operator is notified of the fact by an independent signaling apparatus, whereupon he immediately transfers the connection of the main line to another branch—that is to say, to the one in which is included the cylinder whose matter is to be transmitted next in order. The work of preparing the exhausted cylinder with new matter may then be com-

menced at once. The interval between the completion of the transmission from one cylinder and the commencement of the transmission from the next cylinder in order is thus 5 performed almost instantaneously, as it involves nothing more than the mere changing of a switch from one contact-point to another, and at the same time sending a starting-signal to the operator in charge of the second 10 cylinder.

In order to notify the managing operator when the charging of a cylinder with matter has been completed, I prefer to make use of a 15 signaling apparatus consisting of an electric annunciator placed at the central desk, and a system of independent local conductors extending therefrom to each of the several compartments containing the transmitting apparatuses, each of which compartments is 20 provided with a circuit-closer for actuating the particular annunciator-drop or other visual signal corresponding therewith. Another series of signaling-wires and apparatus is also 25 provided, which latter may consist of an ordinary vibrating bell in each of the compartments, and a corresponding key for closing the circuit of the same at the desk of the managing operator, whereby the latter is enabled to 30 instantaneously notify the transmitting operator when the main line is connected and in readiness for the transmission of the portion of the matter with which the cylinder is charged.

The method of preparing the separate messages for transmission requires a local circuit 35 for each cylinder, and in each of these circuits is included a key and a recording-pen adapted to be operated by an electro-magnet, and to register upon the surface of the cylinder the 40 operations of the key. This is preferably accomplished, as in the Leggo system, before alluded to, by means of spaces corresponding to dots and dashes, which are left between sections of some non-conducting material applied 45 through the agency of the registering-pen. For the purpose of thus registering upon the cylinder the message which is to be transmitted, it is necessary only that a battery be so 50 connected with the key that a circuit may be completed thereby through the coils of an electro-magnet employed for controlling the pen. As there are several of these instruments, however, I prefer to so organize them that they may be all operated by a single battery. 55 The circuits are also rendered interchangeable by means of a switch-board, so that any key may be employed for preparing any of the cylinders. The switch-board is further so organized that any of the registering-circuits 60 may be connected with one of a series of lime-wires belonging to a minor system—such, for instance, as lines in city districts—instead of being connected directly with the return-conductor of the battery. This organization renders 65 the system of service for transmitting directly upon any of the shorter lines of the sys-

tem, without the intervention of the automatic devices. A sounder or other receiving-instrument is therefore preferably included in each of the registering-circuits, for the purpose of 70 rendering each a complete circuit for manual transmission. Each office is further provided with one or more receiving-circuits, with which the main line may be connected when messages are being transmitted thereto from a distant station. Each receiving-circuit is preferably provided with two or more independent automatic receiving-instruments, which may be substituted the one for the other in the event that any one becomes inoperative during the reception 75 of a dispatch.

In receiving messages I prefer to employ the system which is described and claimed in the application above referred to, and which consists, briefly, in placing an opposing battery in the receiving-circuit through which it is necessary for the transmitting-battery to work. This organization is employed for the purpose of overcoming the detrimental effects 85 of static induction. The strength of this opposing battery is to be governed to accommodate the circumstances at any time existing, and it is found necessary to modify it frequently. For this purpose I divide the opposing battery into sections so organized that one, 90 two, or more sections may be connected with the main line, through the receiving-instrument in series, by a simple change in the position of a controlling-switch.

The invention will be more readily understood when considered in connection with the accompanying drawings, in which Figure 1 is a diagram illustrating the organization of circuits and apparatus as adapted to the Leggo system, and Fig. 2 shows certain details of 105 construction.

Referring to the figures, the apparatus grouped at A represents that employed at the central desk in an office of an automatic-telegraph system, and at a' a'' a''' is represented the apparatus at a series of sub-desks or transmitting desks. The main line L of the system enters the office at the central desk A, where it is connected with a switch, B, adapted to continue the connections of the same with either 115 of the various transmitting-instruments, or with a receiving-instrument, C, also located at the office.

Considering first the apparatus at the transmitting-desks a, each of these desks is provided with a cylinder, D, of conducting material, and preferably constructed to be rotated slowly when the message is being prepared for transmission, and more rapidly while the message is being transmitted.

For the purpose of preparing the message a marking-pen, c', is employed, which is adapted to apply a non-conducting ink or gum to the surface of the cylinder when in contact therewith. This marking-pen or stylus normally rests against the cylinder, but is raised therefrom through the action of an electro-

magnet, c^2 , when the latter is vitalized. The coils of the electro-magnet c^2 are respectively included in branch-circuits of a battery, O' , each circuit being also supplied with a key, K , of any suitable form. By simply completing and interrupting the circuit of the battery O' through the aid of any key, K , the corresponding marking-pen will alternately be raised from and press against the surface of the cylinder, thereby causing spaces to intervene between the successive sections of non-conducting material applied to the cylinder by the marking-pen. These spaces depend for their length upon the time that the key is kept depressed, and correspond thus to the dots and dashes of the telegraphic code. The marking-pen and electro-magnet of each cylinder are supported upon a carriage (not shown) which is caused to move longitudinally with reference to the cylinder by means of a threaded rod upon which the carriage is supported. Such a device is illustrated in the Leggo patent referred to. The marking-pen thus applies a spiral line of non-conducting material upon the surface of the cylinder as the latter is revolved, and the interruptions of this line, caused by the depressions of the key K , constitute the dispatch to be transmitted. The method of transmitting consists in causing a contact-point, c^4 , which is connected through a corresponding conductor, l^1 , l^2 , or l^3 , with the switch B , to traverse the surface of the cylinder along the same line traversed by the marking-pen. This contact-point constitutes one electrode of a circuit and the cylinder the other. The point c^4 is for this purpose supported upon the same carriage with the marking-pen c' , each being constructed so that it may be raised out of contact with the cylinder while the other is being employed.

In connection with the transmitting-desk a^3 I have represented, in addition to the key K , a key-board transmitter, k , of well-known construction. It consists, merely, of a series of revolving circuit-closing disks, k' , connected with one pole of the battery O' , and a series of contact springs or brushes, k^2 , connected with a conductor leading to the electro-magnet c^2 . Each disk represents a different character, and is constructed to complete the circuit of the battery when the corresponding contact or circuit closing spring is thrown into the path of the projections k^3 , formed upon its periphery, thereby transmitting impulses corresponding with the character which it is designed to represent. A switch, c^5 , is inserted in the branch conductor 3 , leading to the key K at the desk a^3 . This switch is employed when it is desired to use the key-board transmitter instead of the simple key.

As it frequently happens that it is desired to transmit from one of the desks a directly upon some subsidiary line—such, for instance, as a city line—I provide a switch-board, E . This board is provided with conducting-strips e' , respectively forming the terminals of such

city lines. The conductors 4 , leading from the several desks, are connected with the intersecting rows of contact-disks e^2 . Each transmitting-instrument K may then be placed in connection with any desired subsidiary line by means of switch-plugs in the usual manner, and dispatches may then be sent directly from the key K without the intervention of the cylinder. To avoid the necessity of transmitting through the electro-magnets c^2 when this part of the system is being employed, a switch, c^6 , is placed in each conductor 4 for short-circuiting the coils of the corresponding magnet. A relay or other receiving-instrument, c^3 , is also inserted in each conductor 4 , whereby the operator is enabled to receive communications directly from any line with which he may be placed in connection. The switch-board E is provided with a ground-plate, e^1 , which is connected directly with the earth by a conductor, 5 . The conductors 4 are normally connected by means of the switch-plugs x directly with this ground-plate, and thus through the earth with the negative pole of the battery O' , the positive pole being connected through the conductor 1 with the contact-points of the several keys K .

It may sometimes be desired to connect two of the local circuits with each other for various reasons—as if, for instance, it is desired to employ the key-board transmitter k for the purpose of preparing a dispatch upon another cylinder than that to which it is directly applied. To accomplish this end the switch-board E is provided with an additional conducting-strip, e^3 , in connection with which any one of the conductors 4 may be placed through the agency of the corresponding contact-disk, e^2 , and switch-plug x . Two conductors 4 being thus placed in connection with the same strip, e^3 , the two lines will be connected in series.

Referring now to the plan of transmitting upon the main line the matter which has been transcribed upon the various cylinders, the method whereby the managing operator at the central desk is notified when any cylinder is ready for transmission will first be considered. One pole of a battery, O^2 , is connected through a conductor, 6 , with a series of branch conductors, 7 , respectively traversing the transmitting desks or compartments a , and leading to the central desk A , where they traverse the electro-magnets of an annunciator, M . These magnets are arranged to control the signal-drops corresponding to the desks in a manner well understood.

At each of the desks a is placed a push-button, f , by means of which the circuit of the battery O^2 may be completed through the corresponding branch conductor, 7 , when it is desired to indicate to the managing operator that any particular cylinder is prepared for transmission.

Another system of branch conductors, 8 , leading from one pole of the battery O^2 , is pro-

vided for enabling the central operator to signal any one of the transmitting operators when the apparatus at the central desk is in readiness for the transmission of the messages upon his particular cylinder. For this purpose a push-button, f^2 , is included in each of the branch conductors 8 at the central desk, and a corresponding signal-bell, f^3 , is placed at each of the respective transmitting-desks. 10 The push-buttons f^2 may be marked in any convenient way to designate the desks to which their respective conductors lead.

The conductors $l^1 l^2$, &c., leading from the respective circuit-closing points c^4 , are arranged to be connected with the main line L through the agency of the switch B in the following manner: Each conductor l leads to a corresponding insulated contact-pin, b , projecting from the base b' of the switch B. The switch-arm B^2 is pivoted at the center of the base b' , and the pins b are arranged in a circular series, so that the arm, when revolved, may be placed in contact with any desired pin and allowed to rest upon the same, thereby completing the circuit from the battery O^3 to the corresponding cylinder, and through the conductor l and switch B to the main line L, whenever the contact-point c^4 rests upon the surface of the cylinder. When the contents 30 of any cylinder have been transmitted, the switch-arm B^2 is moved into contact with any other pin b , and the contents of the corresponding cylinder are in like manner automatically transmitted through the agency of the contact-point resting thereon. The managing operator, it will be understood, is able to determine what cylinders are ready for transmission by simply looking at the annunciator-board, for the drops which have been caused to fall when 35 the several operators have signaled the completion of transcribing upon their respective cylinders the messages assigned to them are allowed to remain exposed until the transcribed matter has been transmitted.

40 As it is frequently necessary for the managing operator to communicate directly with the distant station, an independent battery, O^4 , is provided, and one pole of this battery is connected with the earth, while the other pole is connected with a conductor, 9, including a key, F, and sounder or other receiving-instrument, H. The conductor 9 leads to an annular shoulder, b^4 , on the switch B. This shoulder is of such height as to afford a rest for the switch-arm B^2 when the latter is placed between any 45 two pins, but not to be in contact therewith when the arm rests upon any one of those pins. Thus by simply moving the arm B^2 to a position between any two pins b and allowing it 50 to rest there the instruments in the conductor 9 will be placed in readiness for use. When, instead of transmitting, it is desired to receive 55 dispatches at the office represented in the drawings, the switch-arm B^2 is moved into contact with a pin, b^6 , which is similar to the pins b , but which is connected through a con-

ductor, 10, with a chemical or other suitable receiving-instrument, C, of well-known construction. The conductor from this receiving-instrument preferably leads through a portion 70 of a battery, O^5 , to the earth at G', according to the arrangement of apparatus described in my application for patent before alluded to. This battery O^5 is opposed to the battery employed at the transmitting-station, and to a 75 greater or less extent neutralizes the currents therefrom. This is for the purpose of preventing "tailing" at the recording-point or stylus c^8 of the receiver by neutralizing the effects of the static charge and discharge of the 80 line-wire. In practice it is frequently found necessary to change the amount of battery force employed for this purpose; and to more readily accomplish this end I divide the battery O^5 into sections, leading a conductor from 85 each section to a corresponding contact-point, p , of a switch, P. The conductor 10, leading from the receiving-instrument C, is connected with the switch-arm P' of the switch P, and by moving this arm into contact with one or 90 another of the points p the amount of battery force opposed to the transmitting-battery may be adjusted as required. In conjunction with the opposing battery O^5 , I prefer to employ an artificial resistance-circuit, L', for giving to 95 the battery O^5 a complete circuit at all times and maintaining a flow of an opposing current through the instrument C. This resistance-circuit includes an adjustable artificial resistance, T.

100 For the purpose of avoiding any possibility of delay occurring by the reason of the inoperativeness of the receiving-instrument C, another similar instrument, C', may be placed in a branch circuit; 11, and kept in readiness for use. By simply changing the position of a switch-arm, s, from its contact-point s' to the point s^2 this receiving-instrument may be substituted for the instrument C.

110 Although I have described my invention in connection with one particular system of automatic telegraphy, it is evident that it may be applied with good results to various other systems, and I do not desire to confine myself to this particular system, nor to any of the specific forms of apparatus described. It is evident, moreover, that more than one main line, L, may enter the office at the central desk, and be substituted one for the other, as desired.

115 I claim as my invention—

1. The combination of a telegraphic main line, two or more independent automatic transmitting devices, means for preparing said devices with matter for automatic transmission, and means, substantially such as described, for connecting each of said devices with said main line in its proper succession.

2. The combination, with a telegraphic main line, of a terminal station provided with a central managing desk and two or more subsidiary desks, each being equipped with an automatic transmitting device, means for preparing said

devices with matter for automatic transmission, electric signaling apparatus for transmitting signals to and from the central desk, and means for connecting any one of said transmitting devices with said main line.

5 3. The combination of a main line, two or more independent automatic transmitting-instruments, a switch for placing any one of said transmitting-instruments in connection with 10 said main line at pleasure, a battery, and a series of two or more branch conductors leading therefrom, for preparing the messages to be transmitted from said automatic transmitting-instruments, a series of subsidiary main 15 lines, and a switch by means of which any one of said branch conductors may be connected with any one of said subsidiary lines.

4. The combination of two or more automatic

transmitting-cylinders, a transmitting-stylus applied to each of said cylinders, a main battery, a main line, means, substantially such as described, for charging each of said cylinders with matter for automatic transmission, a switch for placing any one of said styluses in connection with said main line, an annunciator 20 located near said switch, and means, substantially such as described, whereby the respective drops and said annunciator may be actuated from a point near said cylinders.

In testimony whereof I have hereunto subscribed my name this 14th day of September, 30 A. D. 1883.
